UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT INTERRUPTER.

Application filed December 22, 1919. Serial No. 346,779.

My invention relates to circuit interrupters and particularly to quick-acting circuit interrupters.

One object of my invention is to provide a circuit interrupter that shall open quickly.

Another object of my invention is to provide a circuit interrupter that shall move a relatively small distance when opening and thus preclude excessive stresses, such as might occur by reason of the momentum of moving parts having large inertia.

A further object of my invention is to provide a circuit interrupter that shall be simple, compact and rugged in construction and quick and positive in operation.

In practicing my invention, I provide a circuit interrupter having an operating handle, laminated copper brushes that constitute the stationary contact members, a solid copper plate, reinforced by steel plates, that constitutes the movable contact member, auxiliary arcing contact members, an arc chute and a magnetic blowout device associated therewith, an electromagnet that is adapted to hold the circuit interrupter closed, a plurality of springs adapted to be so compressed by the closure of the circuit interrupter as to accelerate the opening thereof when the circuit interrupter is released.

An auxiliary winding is connected across the terminals of a reactor in the circuit that is to be protected and is so disposed, with respect to the air gap of the electromagnet, as to shift the flux that normally traverses the armature, to an auxiliary path to thus render the armature non-responsive to the electromagnet. The compressive force of the springs, being transmitted directly to the movable member of the interrupter, immediately actuates the same when the auxiliary winding is energized.

Figure 1 in the accompanying drawings is a side view, partially in elevation and partially in section, of a circuit interrupter embodying my invention, Fig. 2 is a plan view of the electromagnet shown in Fig. 1; Fig. 3 is a diagram of the connections of the electromagnet to the circuit. Fig. 4 is a plan view of the electromagnet and its supporting member, and Fig. 5 is a plan view of the arc chutes and of the magnetic blow-out device shown in Fig. 1.

A circuit interrupter that is mounted on

panel 2 comprises an operating handle 3, 55 stationary contact members 4 and 5, a movable contact member 6, auxiliary arcing contact members 7 and 8, an arc chute 9, a magnetic blowout device 10 and an electromagnet 11. The operating handle 3 is pivotally 60 mounted on a shaft 12 that is mounted in a supporting casting 13. The movable contact member 6 is pivotally mounted on a shaft 14 that is supported by the casting 13. The operating handle 3 is adapted to close 65 the circuit interrupter 1, through a toggle-link mechanism 15, by the pressure of a cam member 16 against the movable contact member 6. A spring 17 is so disposed between 70 the shaft 12 and the handle 3 as to return the operating handle 3 to its initial position after the circuit interrupter 1 has been closed, in order that the link mechanism 15 may not retard the quick opening movement of the 75 movable member 6. A bumper 18 is provided to serve as a stop member for the movable contact member 6 when the circuit interrupter 1 opens. The stationary contact members 4 and 5 comprise laminated copper 80 brushes that are so disposed, when the circuit interrupter opens, that the movable contact member 6 becomes disengaged from the stationary contact member 5 before it passes out of engagement with the stationary contact member 4. The auxiliary arcing contact member 8 is pivoted at 8^a to the bridging member 6 and is yieldingly held in advanced position by a spring 8^b so that the auxiliary arcing contact members 7 and 8, 85 however, remain in engagement until the movable contact member 6 and the stationary member 5 become disengaged. The arc that is drawn when the arcing contact members 7 and 8 become disengaged is enclosed by an arc chute 9 that is disposed vertically 90 above the arcing members 7 and 8 and is provided with the usual insulating walls 9^a. The magnetic blowout device 10 comprises a magnetizable core 19 and a winding 20. The magnetic field produced by the magnetizable core 19 and that produced by the 100 current traversing the arc so react as to force the arc upward and thus cause it to break. The winding 20 is electrically and mechanically connected to the stationary contact 105 member 5 through a casting 20^a and serves as a terminal stud therefor.

The electromagnet 11 comprises a mag-

netizable core member 21, an armature 22, a potential winding 23 for energizing the core 21 and an auxiliary winding 24 that is disposed around arms 25 for so shifting the flux that normally traverses the armature 22, through the path comprising the arms 25, as to render the armature 22 non-responsive to the core member 21. The auxiliary winding 24 is connected across the terminals of a reactor 26 that is connected in series with the circuit 27 which is to be protected. A rod 28 extends through the panel 2 and connects the armature 22 to the movable contact member 6. A spring 29 is slidably mounted on the rod 28, between the front face of the panel 2 and the movable contact member 6. A casting 30, on the rear of the panel 2, supports the electromagnet 11 which is secured to the casting by bolts 11^a (Fig. 4).

When the circuit interrupter 1 is closed by the operating handle 3, the electromagnet 11 holds the armature 22 and maintains the circuit interrupter 1 closed against the force of the springs 29. The auxiliary winding 24 of the electromagnet 11 is energized by the increased voltage that is produced across the terminals of the reactor 26 when the current traversing the circuit interrupter 1 is increased quickly. The flux that normally traverses the armature 22 is shifted to the auxiliary path, through the arms 25, by the auxiliary winding 24, and the armature 22, being no longer responsive to the electromagnet 11, is disengaged from the core 21, and the circuit interrupter is opened by the direct force of the compressed springs 29. The bumper 18 limits the movement of the movable member 6, and the use of the auxiliary arcing contact members 7 and 8 obviates the necessity for a large separating movement. The movable contact member 6 is made of a solid copper plate 31 secured to, and reinforced by, a block 32.

Although I have shown only one form of circuit interrupter embodying my invention, I do not wish to limit it to the structure shown, as various modifications may be made therein without departing from the spirit and scope of the invention as set forth in the appended claims.

I claim as my invention:

1. In a circuit interrupter, the combination with an operating handle, of a movable bridging member adapted to be actuated thereby, a plurality of resiliently mounted contact members adapted to be bridged by the bridging member, an electromagnet, an armature associated therewith for holding the circuit interrupter in its closed position, a rod joining the armature and the movable bridging member, a winding for rendering the armature non-responsive to the electromagnet, and a spring mounted on the rod

for quickly opening the circuit interrupter when the armature is released by the electro-magnet.

2. In a circuit interrupter, the combination with an operating handle, of a movable bridging member adapted to be actuated thereby, a plurality of resiliently mounted contact members adapted to be bridged by the bridging member, an electromagnet, an armature associated therewith, a winding for energizing the electromagnet, a second winding for rendering the armature non-responsive to the electromagnet, a rod joining the armature and the movable bridging member, and a spring for quickly opening the circuit interrupter when the armature is released by the electromagnets.

3. In a circuit interrupter, the combination with an operating handle, of a panel, a plurality of stationary and movable contact members supported at one side of the panel, a holding magnet disposed at the other side of the panel, a winding for energizing the magnet, an armature adapted to be held by the magnet, a connection between the armature and the movable contact member whereby the circuit interrupter is held closed, a winding for rendering the armature non-responsive to the electromagnet, and means for opening the circuit interrupter upon the release of the armature.

4. In a circuit interrupter mounted on a panel, the combination with an operating handle on the front of the panel for closing the circuit interrupter, of an electromagnet on the rear of the panel for holding the circuit interrupter closed, a winding for energizing the electromagnet, a plurality of stationary and movable contact members, a rod extending from the movable contact member through the panel to an armature of the electromagnet and adapted to hold the circuit interrupter closed while the armature is responsive to the electromagnet, a winding responsive to a quick change of current through the circuit interrupter for rendering the armature non-responsive to the magnet, a spring for quickly opening the circuit interrupter upon the rendering of the armature non-responsive to the electromagnet, and a stationary and a movable arcing contact member.

5. A circuit interrupter comprising a panel, a pair of stationary contact members, a bridging member for the contact members, means for moving the bridging member to closed position, a holding magnet disposed at the side of the panel, opposite to the side occupied by the other portions of the apparatus, an armature co-operating with the magnet, a connecting member extending through the panel and having its ends joined to the bridging member and the armature, and a yielding member interposed between the bridging mem-

ber and the panel in position to be compressed when the bridging member is moved to closed position, the said yielding member acting to open the interrupter when the armature is released by the magnet.

6. A circuit interrupter comprising a panel, a pair of stationary contact members, a bridging member for the contact members, an operating lever for moving the bridging member to closed position, means for returning the said lever to retracted position when the bridging member has been closed, a holding magnet disposed at the side of the panel opposite to the side occupied by the other portions of the apparatus, an armature co-operating with the magnet, a connecting member extending through the panel and having its ends joined to the bridging member and the armature, and a yielding member interposed between the bridging member and the panel in position to be compressed when the bridging member is moved to closed position, the said yielding member acting to

open the interrupter when the armature is released by the magnet.

7. A circuit interrupter comprising a panel, a pair of stationary contact members, a bridging member for the contact members, means for moving the bridging member to closed position, a holding magnet disposed at the side of the panel opposite to the side occupied by the other portions of the apparatus, an armature co-operating with the magnet, a connecting member extending through the panel and having its ends joined to the bridging member and the armature, and a yielding member connected to the bridging member and a fixed support and arranged to be stressed when the bridging member is moved to closed position, the said yielding member acting to open the interrupter when the armature is released by the magnet.

In testimony whereof, I have hereunto subscribed my name this 17th day of December, 1919.

CHRISTIAN AALBORG.
